UNITED STATES PATENT OFFICE.

JOSE A. DOMINGUEZ, OF MAYAGUEZ, PORTO RICO.

DESIGN FOR A WATCH CHARM OR SIMILAR ARTICLE.

Application filed May 2, 1927. Serial No. 21,813. Term of patent 14 years.

To all whom it may concern:

Be it known that I, Jose A. DOMINGUEZ, a citizen of the United States, and a resident of Mayaguez, Porto Rico, have invented a new, original, and ornamental Design for Watch Charms or Similar Articles, of which the following is a specification, reference being had to the accompanying drawings forming a part thereof.

In the drawings

Figure 1 is a side elevation of a watch charm or similar article showing my new design.

I claim:

The ornamental design for a watch charm or similar article, as shown.

JOSE A. DOMINGUEZ.
